UNITED STATES PATENT OFFICE.

OTTO A. HOKANSON, OF WOODSTOCK, ILLINOIS, ASSIGNOR TO WOODSTOCK TYPEWRITER COMPANY, OF WOODSTOCK, ILLINOIS, A CORPORATION OF ILLINOIS.

TYPEWRITER.

Application filed June 5, 1920. Serial No. 386,887.

To all whom it may concern:

Be it known that I, OTTO A. HOKANSON, a citizen of the United States, and a resident of Woodstock, in the county of McHenry and State of Illinois, have invented 5 certain new and useful Improvements in Typewriters, of which the following is a specification.

This invention relates generally to typewriter mechanism and more especially to line lock and signal mechanism for controlling the operation of the typewriter as the platen approaches the limit of its movement.

15 The invention has for its object the provision of mechanism of the character named which shall be of improved construction and operation, and it is exemplified in the combination and arrangement of parts shown in 20 the accompanying drawings and described in the following specification and is more particularly pointed out in the appended 25 claims.

In the drawings,

25 Fig. 1 is a side elevation of a portion of a typewriter having one embodiment of the present invention applied thereto;

Fig. 2 is a fragmentary top plan view of 30 a portion of the mechanism shown in Fig. 1;

Fig. 3 is a horizontal section substantially on line 3—3 of Fig. 6;

Fig. 4 is a fragmentary vertical section substantially on line 4—4 of Fig. 3;

Fig. 5 is a sectional view on line 5—5 35 showing a detail of construction; and

Fig. 6 is a vertical section substantially on line 6—6 of Fig. 3.

Fig. 7 is a fragmentary front elevation of the universal bar and type bar guide.

40 While the present invention is applicable to various forms of typewriters, it is especially adapted for use in connection with a typewriter having a folding platen carriage support and is shown in the drawings 45 as applied to such a form of typewriter. In the embodiment of the invention illustrated the numeral 10 designates the base frame of the typewriter having a pair of arms 11 pivoted at 12 thereon for supporting the platen carriage frame. A platen carriage base plate 13 is secured to the arms 11 adjacent their ends and a platen carriage 14 is mounted on the base 13 to travel longitudinally thereof. The movement of 55 the platen carriage is controlled by an es-

capement wheel 15 having a pinion 16 meshing with a rack 17 connected with the platen carriage. The escapement wheel 15 is controlled by a dog rocker 18 pivoted on a bracket 19 connected with the lower face of a supporting plate 20 secured to the lower surface of the platen carriage frame 13. The dog rocker 18 carries a fixed dog 21 and a movable dog 22 and is oscillated by a plate 23 which forms the lower arm of a bell crank lever having an upwardly extending arm 24 extending into the path of movement of the type bars. When the arm 24 is struck by a type bar, it is moved to the right, as viewed in Fig. 6, thus swinging the plate 23 downwardly. The plate 23 carries a tongue 25 which engages a tail-piece 26 connected with the dog rocker 18. The movement of the plate 23 will therefore swing the dog rocker 18 downwardly 70 to shift the contact with the escapement wheel 15 from the movable dog 22 to the fixed dog 21. When the type bar rebounds the arm 24 returns to its initial position and the dog rocker 18 is also returned to position 75 by a spring 27, thus freeing the escapement wheel 15 and permitting it to rotate until it is stopped by engagement with the movable dog 22.

When the platen nears the limit of its movement, it is desirable to automatically prevent further operation of the type upon the paper and this is done by controlling the arm 24 so that when it is struck by a type bar, it will not move rearwardly to 80 permit the type to strike the platen, but will be held in the position shown in Fig. 6 and thus stop the movement of the type bar before an impression is made upon the paper. The mechanism for holding the arm 85 24 in locked position is controlled by a stop 28 adjustably mounted on a margin stop bar 29 which is supported at the rear of the platen carriage by levers 30 pivotally mounted at 31 on the end plates 32 of the carriage. The stop 28 comprises a relatively thin metal sheet bent to form a band surrounding the bar 29 and having a vertical dimension somewhat greater than the vertical thickness of the bar. A leaf spring 105 33 is interposed between the upper face of the bar 29 and the upper wall of the stop 28, as shown in Fig. 4, and the lower wall of the stop is provided with a lug 34 arranged to engage notches 35 in the bar 29. 110

The stop 28 may be adjusted along the bar 29 by pressing downwardly on a finger piece 36 to free the lug 34 from the notches 35, and when the bar is moved to the desired position, the spring 33 will automatically re-engage the lug 34 with one of the notches 35. An arm 37 extends downwardly from the stop 28 and carries a foot plate 38 beveled at one edge, as shown at 39. A pin 40 is carried by the foot plate 38 and extends downwardly as shown in Figs. 1 and 4.

A bell crank lever 41 is pivoted at 42 on the lower face of the platen carriage bed plate 13 and is provided with an upwardly bent flange 43 which extends into the path of movement of the foot piece 38 on the stop 28. The bell crank 41 has a slot 44 formed therein for limiting the movement thereof and is also provided with a disc-shaped bearing 45 which co-operates with the bifurcated end of an arm 46 on a bell crank lever 47 pivoted at 48 on the plate 13. An arm 49 of the bell crank lever 47 projects forwardly and carries a link 50 pivoted at 51 to the forward end of the arm 49. The end of the link 50 opposite its pivotal connection 51 is provided with a hook 52 extending upwardly through a slot 53 in the bracket 13, as shown in Figs. 5 and 6, so that the nose piece of the hook 52 rests upon the upper face of the plate 13 and supports the end of the link 50. A flange 54 projects forwardly from the lower edge of the link 50 so that in one position of the link the flange 54 extends beneath the arm 23 of the universal member 24, as shown in Figs. 5 and 6. When the flange 54 is in this position the arm 23 will be locked against downward movement so that when the universal member 24 is struck by the type bars it will stop the movement of the bars before the type engage the platen. In this position of the link 50 the dog rocker 18 will also be held against movement since the dog rocker is connected with the plate 23 by the tail piece 26. A spring 55 is connected with the bell crank lever 41, as shown in Fig. 3, and normally holds the link 50 in a retracted position so that the flange 54 is disengaged from the plate 23 leaving the plate free to operate. When, however, the platen carriage approaches the end of its movement the foot plate 38 will strike the contact member 43 of the bell crank 41 and shift the bell cranks 41 and 47 and the link 50 into the position shown in Figs. 5 and 6 so that the universal member 24 will be locked preventing further writing or movement of the platen.

If it is desired to release the line locking mechanism, in order to extend the writing still further into the margin, this may be done by swinging the stop bar 29 rearwardly until the foot plate 38 clears the contact member 43. This will release the bell crank 41 so that it will be drawn by

the spring 53 into position to free the line locking mechanism and at the same time the contact member 43 will be brought into position to engage the front face of the foot plate 38 thus holding the bar 29 in its rearward position so that the platen may continue to move until it is brought to rest by a limit stop. For swinging the stop bar 29 rearwardly a line lock release lever 56 is provided which is a continuation of the arm 30 upon which the bar 29 is supported. By pressing downward upon the lever 56 the bar 29 is swung rearwardly to disengage the foot plate 38 from the contact member 43, thus releasing the line locking mechanism.

In order to warn the operator when the platen is approaching the end of the line, a signal bell 57 is secured to the lower face of the plate 13 and is provided with a tapper 58 pivoted at 59 on a bracket 60 secured to the plate 13 by screws 61. The arm of the tapper 58 extends beyond its pivot 59 and is connected with the spring 55, as shown in Fig. 3, so that the tapper is normally held in the position indicated in that figure. A contact finger 62 secured to the tapper 58 extends into the path of movement of the pin 40 on the stop 28. As the pin 40 engages the face 63 of the contact finger 62, the tapper 58 will be swung in a counter-clockwise direction, as viewed in Fig. 3, until the pin 40 has passed the contact finger 62. The tapper will then be released and will be swung by the spring 55 and carried by its momentum until it strikes the signal bell 50. A pin 64 is provided to engage the tapper arm near its pivot and impart a free stroke to the ball at the end of the tapper. The contact finger 62 is provided with a beveled face 65 which engages the pin 40 during the reverse movement of the platen carriage and stop bar 29 so that the bar will be deflected outwardly to free the contact finger 62 on its return movement.

The beveled edge 39 on the foot plate 38 swings the bar 29 outwardly in a similar manner to permit the stop 28 to pass the contact member 43 on the return movement of the platen in cases where the release lever 56 has been operated to permit the stop 28 to pass the contact member 43 for writing in the margin.

I claim:

1. In a typewriter, a member having a portion thereof disposed at a point common to the paths of movement of the type bars, and means for holding said member against movement to prevent printing operations when said typewriter approaches the end of a line.

2. In a typewriter, a lever having one arm thereof arranged at a point common to the paths of movement of the type bars, a movable platen carriage for said typewriter, and mechanism controlled by said

platen carriage for intercepting the opposite arm of said lever to prevent printing operation when said platen carriage approaches a limiting position.

5 3. In a typewriter, a platen carriage support movable into and out of operating position, a universal member comprising a bell-crank lever mounted on said support and movable therewith, a platen carriage 10 on said support, and mechanism mounted on said support and controlled by said platen carriage for restricting the movement of said universal member to prevent printing operations of said typewriter 15 when said platen carriage approaches a limiting position said mechanism comprising a stop movable into the path of one end of said bell-crank lever.

4. In a typewriter, a platen carriage 20 frame having a platen carriage movably mounted thereon, escapement mechanism for controlling said platen carriage, a universal member comprising a lever mounted on said platen carriage frame and having one 25 arm thereof extending into a common point in the paths of the type bars and arranged to be struck by said bars for actuating said escapement mechanism, and means controlled by said platen carriage for restricting 30 the movement of said universal member to prevent operation of said escapement mechanism when said platen carriage approaches a limiting position said restricting means comprising a stop movable into and 35 out of the path of said lever and a guide for said stop arranged to prevent movement thereof under the force of the blows of the type bars on said lever.

5. In a typewriter, a platen carriage 40 frame movable into and out of operative position, a platen carriage movably mounted on said frame and having a platen supported thereby, a lever pivoted on said frame and having a portion thereof extending into the path of movement of the typebars of said typewriter adjacent said platen, mechanism mounted on said frame for holding said lever in position to check 45 the movement of the type bars of said typewriter to prevent the type from striking said platen, and means controlled by said 50 platen carriage for actuating said holding mechanism to lock said lever when said platen carriage approaches a limiting 55 position.

6. In a typewriter, a platen carriage frame, a platen carriage movably mounted on said frame, a lever pivoted on said frame and having a portion thereof extending 60 into the path of movement of the type bars of said typewriter so that said lever is actuated by said type bars, escapement mechanism actuated by said lever for controlling the movement of said carriage, a 65 stop movable into and out of the path of

said lever to hold said lever against movement by the type bars, and mechanism arranged to be operated by said platen carriage as it approaches a limiting position for shifting said stop to move said stop 70 into position to hold said lever.

7. In a typewriter, a platen carriage, a stop bar mounted on said carriage and movable in one direction out of normal position, a stop carried by said bar, a signal 75 device having a contact member arranged to be engaged by said stop to actuate said device when said platen carriage approaches a limiting position, and means for swinging said stop bar out of normal position to permit said stop to pass said contact member on the return movement of said carriage.

8. In a typewriter, a platen carriage 80 frame, a platen carriage movably mounted on said frame, a signal device comprising an arm having a contact member pivoted on said frame, a stop bar pivotally supported by said carriage to swing into and out of operating position, and a stop on said bar 85 for engaging said contact member to actuate said signal device when said platen carriage approaches a limiting position, said contact member having a beveled face thereon for engaging said stop on the return movement of said platen carriage to swing said bar and stop into position to permit said stop to pass said contact member. 90

9. In a typewriter, a platen carriage 95 frame, a platen carriage movably mounted on said frame, line lock mechanism having a contact member for actuating said mechanism, a signal device having a contact member for actuating said device, a stop bar movably mounted on said platen carriage and having a stop thereon arranged to successively engage said contact members as said platen carriage approaches a limiting position, and means for shifting said stop bar during the return movement of 100 said carriage to permit said bar to pass said contact members. 105

10. In a typewriter, a platen carriage frame, signal mechanism and line lock mechanism mounted on said frame, a platen carriage arranged to travel on said frame, a stop bar movably supported by said carriage and having a stop thereon for successively actuating said signal mechanism and said line lock mechanism as said carriage 110 approaches a limiting position, manually operated means for shifting said stop bar to free the stop thereon from said line lock mechanism, and means for automatically shifting said stop bar during the return movement of said carriage to permit the stop thereon to pass said line lock and signal mechanisms. 115 120

11. In combination, a platen carriage 125 frame, line lock mechanism comprising a 130

lever pivotally mounted on said frame, signal mechanism comprising an arm pivotally mounted on said frame, and a single spring connected with said lever and arm for resiliently holding said lever and arm in their normal positions.

12. In a typewriter, a platen carriage frame, means for supporting said frame for movement into and out of operating position, a platen carriage and platen mounted to travel along said frame, a universal member pivotally mounted on said frame and having an arm extending into the path of movement of the type bars, escapement mechanism mounted on said frame for controlling the movement of the platen thereon, means actuated by said universal member when struck by a type bar for operating said escapement mechanism, mechanism mounted on said frame for locking said universal member to prevent operation of said escapement mechanism and to intercept the type bars when said platen carriage has moved to a position to approach the end of a line, a stop bar movably mounted on said platen carriage and having a stop thereon for actuating said locking mechanism, and means for shifting said stop bar to free said stop from said locking mechanism to permit further operation of said typewriter to print beyond the margin line.

13. In combination, a typewriter having a platen carriage frame movable into and out of operating position, a platen carriage movably mounted on said frame, escapement mechanism on said frame for controlling the movement of said carriage, a universal member mounted on said frame for operating said escapement mechanism and having a portion thereof projecting into the path of the type bars of said typewriter, a device for locking said universal member to prevent operation of said escapement mechanism and said type bars, means mounted on said frame for moving said device into locking position, signal mechanism mounted on said frame, and a stop bar connected with said carriage and having a stop thereon arranged to successively actuate said signal mechanism and the operating means for said locking device as said carriage approaches a limiting position, said escapement mechanism, universal member, lock-

ing device and operating mechanism therefor, signal mechanism, platen carriage, stop bar and stop being all connected with said platen carriage frame and movable therewith into and out of operating position.

14. Line lock mechanism for typewriters comprising a pair of bell-crank levers having pivotally connected arms, a contact member on one of said levers for engaging a margin stop, and locking mechanism actuated by the other of said levers to prevent writing operation by said typewriter.

15. In a typewriter, a platen carriage frame, a pair of horizontally disposed bell-crank levers pivotally mounted on said frame and having adjacent arms thereof operatively engaging one another, the free arm of one of said levers being disposed in the path of movement of the stop of the platen carriage of said typewriter, and locking mechanism actuated by the free arm of the other of said bell-crank levers for preventing writing operations of said typewriter.

16. In a compactable typewriter, a platen carriage frame having a portion thereof horizontally disposed when said platen carriage frame is in operative position, a platen carriage mounted on said frame and having a margin stop thereon, a horizontally disposed bell-crank lever mounted on said platen carriage frame and having one end thereof extending into the path of said margin stop, means for limiting the movement of said bell-crank lever, a spring for holding said bell-crank lever at one extremity of its path of movement, a second bell-crank lever pivotally mounted on said platen carriage frame and operatively engaging the other arm of said first-mentioned bell-crank lever, and line lock mechanism arranged to be actuated by said second bell-crank lever.

17. In a typewriter, a member interposed in the paths of movement of the type bars at a point common to said paths, and means for holding said member against movement to prevent printing operations when said typewriter approaches the end of a line.

In testimony whereof I have signed my name to this specification on this 3d day of June, A. D. 1920.

OTTO A. HOKANSON.
